CHAMBERED SOAKING PIT

Herbert Schaefer, Luxemburg, Luxemburg

Application February 4, 1949, Serial No. 74,574
In Luxemburg June 21, 1948

4 Claims. (Cl. 263—40)

1

In the existing chambered furnaces in which the products to be heated are inserted through the top and which are adapted to reheat the air and the gas in continuous recuperators, the flame of the burners is projected horizontally into the chamber of the furnace above the products to be heated and travels towards the bottom where it is exhausted through openings at the base of the side walls.

This produces a difference in the temperatures of the top and the bottom of the products to be heated. Furthermore, in order to prevent the top of the ingots from being overheated, they must be prevented from coming into direct contact with the flame issuing from the burners and sufficient space must be left above the ingots to serve as a combustion chamber for the flames in course of formation. It is therefore necessary to give the chamber a great depth, which is not always compatible with the arrangement of the premises.

The present invention has for its object to obviate these drawbacks by providing a perfect circulation of the flames and a uniform temperature in the furnace owing to the arrangement of the burner and the flues relatively to the chamber of the furnace.

The combustion chamber is located at one end of the furnace and is so shaped as to form an inclined cylindrical surface or an upwardly flaring conical surface. The exit flues are located at the bottom of the opposite wall near the level of the hearth. Thus the flames enter the furnace and the products of combustion quit the furnace in a close level to the hearth.

The combustion supporting agent and the fuel are conveyed to the base of said combustion chamber and the flame issues vertically from the bottom towards the top. It spreads out in fan shape along the cylindrical or conical wall of said chamber and extends over the entire width of the furnace before coming into contact with the products to be heated.

The wall opposite the burner may be vertical or so shaped as to favour the return of a portion of the flames towards the burners so as to activate the natural circulation which is set up of its own accord by the location of the burner and the exit flues and any difference of temperature so long as the temperature is not uniform throughout the whole chamber of the furnace. The side walls of the chamber of the furnace may also be shaped so as to favour the circulation of the flames.

If it is desired to remove the slag which is formed at high temperature, an outflow opening may be provided at the base of the wall opposite the burners between two smoke flues. This wall of the furnace receives the radiation of the inclined surface of the combustion chamber and is continually licked by the flames. The slag

2

therefore remains very hot and can be removed without difficulty in a molten state.

The smoke flues are located at the base of the wall opposite the burners.

5 One embodiment of the present invention is illustrated in Figs. 1, 2 and 3, which show an example of a furnace in which the air is re-heated in a recuperator through which the flames issuing from the furnace are adapted to pass.

10 Fig. 1 is a section along the line A—B of Fig. 2.

Fig. 2 is a plan view of the chamber of the furnace and of the recuperator, with the cover and the accessory members such as the gas cock, the fan and the gas manifold removed.

Fig. 3 is a section along the line E—F of Fig. 2, showing the profile of the side walls.

In Fig. 1 the gas is supplied through the manifold 1, the cock 2, the pipe 3, the flue 4 and issues vertically into the chamber 5. The hot air from the recuperator is sucked by the fan 6 and driven through the pipe 7 and suitable devices into the chamber 5 where it encounters the gas.

The flame issues vertically into the chamber of the furnace 8, the wall 9 of which is arranged 25 so as to form a cylindrical or conical surface. The flame spreads against this wall and follows the path indicated by the arrows 10.

The chamber of the furnace is closed by the movable cover 11. The wall 12 opposite the burners may be vertical, inclined, or of a suitable profile, such as is shown in Fig. 1, which favours the return of the flames towards the burner.

Part of the flames escapes through the openings 13 at the base of the wall 12, follows the 35 flues 14 and reaches the distribution chamber 15 of the recuperator 16, whence it flows into the manifold 17 and then into the flues 18 connected to the chimney.

Between the two openings 13, a hole 19 is provided for the outlet of the slag, which enables the same to be removed in the molten state.

The circulation of the flames in the direction of the arrows 10 is more active as the differences of temperature between the top and the bottom 45 and the two opposite walls are more marked. This causes the temperatures to become very quickly uniform over the entire height of the furnace. The side walls 20 (Fig. 3) may be so shaped as to provide passages along the masonry 50 at the base of the walls, for the return of the flames. The transverse section of the furnace is thereby increased, which activates the circulation of the flames adjacent the hearth.

Several identical furnaces may be joined together as shown in Figs. 2 and 3, thereby considerably reducing the losses of heat through the walls and also the cost of the plant.

There may be one or more smoke outlet openings at the base of the wall opposite the burner; 60 likewise several burners may be provided at one end of the furnace according to the fuel employed.

I claim:

1. A soaking pit furnace comprising a heating chamber having an open roof for introduction of the products to be heated, a flat cover for said opening in the roof, a single combustion chamber located at one end of said heating chamber and opening freely into same throughout the major part of its height, the bottom of said combustion chamber being at substantially the same level as the hearth of the heating chamber and its rear wall assuming a sharp slope extending substantially between the outer lower end of the bottom of the combustion chamber and a line near the roof of the heating chamber defining the upper end of the opening between the heating chamber and the combustion chamber, a vertical well opening into the outer end of the bottom of the combustion chamber, means for feeding air and fuel into the lower end of said vertical well the combustion of which will produce vertical flames which are adapted to sweep over the rear wall of the combustion chamber, to spread throughout the width thereof, to mix through induction with the combustion products near the hearth, to enter the heating chamber tangentially with the cover thereof, and to return along a substantially closed elliptical path towards said combustion chamber, and exit flues opening into the heating chamber just above the hearth thereof in the solid wall of the heating chamber opposite the combustion chamber and through which a fraction of the gases conveyed by the flames is exhausted.

2. A soaking pit furnace comprising a heating chamber having an open roof for introduction of the products to be heated, a flat cover for said opening in the roof, a single combustion chamber located at one end of said heating chamber and opening freely into same throughout the major part of its height, the bottom of said combustion chamber being at substantially the same level as the hearth of the heating chamber and its rear wall assuming a sharp slope extending substantially between the outer lower end of the bottom of the combustion chamber and a line near the roof of the heating chamber defining the upper end of the opening between the heating chamber and combustion chamber, a vertical well opening into the outer end of the bottom of the combustion chamber, means for feeding air and fuel into the lower end of said vertical well, the combustion of which will produce vertical flames which are adapted to sweep over the rear wall of the combustion chamber, to spread throughout the width thereof, to mix through induction with the combustion products near the hearth, to enter the heating chamber tangentially with the cover thereof and to return along a substantially closed elliptical path towards said combustion chamber, the solid wall of the heating chamber opposed to the combustion chamber being recessed towards the middle of its height to further the sweeping movement of the flames over it, and exit flues opening into the heating chamber just above the hearth thereof in the solid wall of the heating chamber opposite the combustion chamber and through which a fraction of the gases induced by the flames is exhausted.

3. A soaking pit furnace comprising a heating chamber having an open roof for introduction of the products to be heated, a flat cover for said opening in the roof, a single combustion chamber located at one end of said heating chamber and opening freely into same throughout the major part of its height, the bottom of

said combustion chamber being at substantially the same level as the hearth of the heating chamber and its rear wall assuming a conical shape having its apex substantially above the center of the opening in the roof and extending substantially between the outer lower end of the bottom of the combustion chamber and a line near the roof of the heating chamber defining the upper end of the opening between the two chambers, a vertical well opening into the outer end of the bottom of the combustion chamber, means for feeding air and fuel into the lower end of said vertical well, the combustion of which will produce vertical flames which are adapted to sweep over the rear wall of the combustion chamber, to spread throughout the width thereof, to mix through induction with the combustion products near the hearth, to enter the heating chamber tangentially with the cover thereof and to return along a substantially elliptical path towards said combustion chamber, and exit flues opening into the heating chamber just above the hearth thereof in the solid wall of the heating chamber opposite the combustion chamber and through which a fraction of the gases induced by the flames is exhausted.

4. A soaking pit furnace comprising a heating chamber having an open roof, a flat cover for said opening in the roof, a single combustion chamber located at one end of said heating chamber and opening freely into the same throughout the major part of its height, the bottom of said combustion chamber being at substantially the same level as the hearth of the heating chamber and its rear wall assuming a conical shape having its apex substantially above the center of the opening in the roof and extending substantially between the outer lower end of the bottom of the combustion chamber and a line near the roof of the heating chamber defining the upper end of the opening between the two chambers, a vertical well opening into the outer end of the bottom of the combustion chamber, means for feeding air and fuel into the lower end of said vertical well, the combustion of which is adapted to produce vertical flames which are adapted to sweep over the rear wall of the combustion chamber, to spread throughout the width thereof, to mix through induction with the combustion products near the hearth, to enter the heating chamber tangentially with the cover thereof and to return along a substantially elliptical path towards said heating chamber, the side walls of the heating chamber including a receding lower portion, and exit flues opening into the heating chamber just above the hearth thereof in the solid wall of the heating chamber opposite the combustion chamber and through which a fraction of the gases induced by the flames is exhausted.
